LOUISIANA.

BOTTLE-COOLING DEVICE.

Application filed July 31, 1925. Serial No. 47,318.

Our present invention relates to improvements in means for handling bottled beverages of the type in which they are stored under refrigerating or cooling conditions.

5 The invention aims to provide a simple, economical, and efficient means by which a large number of bottles may be retained within a cooling chamber and readily inserted therein and removed therefrom.

10 The invention further aims to provide an apparatus of this kind in which one or more units may be used at will in connection with any ordinary refrigerator box, being readily inserted therein and removed therefrom individually or collectively as desired.

15 With these and other objects in view, the invention comprises the novel features of construction, and arrangement and combination of parts hereinafter described, and defined by the appended claims.

In the drawings:

Figure 1 illustrates a plan view of an ordinary ice box, with the cover removed.

Fig. 2 is a transverse section on line 2—2
25 of Fig. 1.

Fig. 3 is a transverse vertical sectional view of one of the units.

Fig. 3^a is a sectional view corresponding to the lower portion of Fig. 3 with the movable parts in a different position.

Fig. 4 is a sectional detail.

Referring by reference characters to this drawing, the numeral 1 designates the ice box which is intended to be representative of any desired form of top opening ice box or refrigerator, and 2 designates a plurality of bottle handling units therein. Any number of these may be inserted in the ice box and grouped in any desired manner therein, 40 ten being shown for convenience, arranged to leave a central space free for ice.

Each of the units 2 comprises a receptacle divided into two compartments 2^a and 2^b by a transverse partition wall 2^c, the receptacle being of such shape that each of the compartments is adapted to receive and hold bottles of the size or type desired, such bottles being indicated at 4. The container or receptacle is made open at the bottom, as it is intended that it shall be used in connection with an ice box filled with water, as we find the best cooling effects are secured by having the bottles submerged in ice water,

and to hold the container elevated above the bottom of the ice box so that water will have free access to the interior compartments thereof, it is provided with feet or projections indicated at 2^d. One of these compartments, 2^a is designated as a receiving compartment, and the other, 2^b, as a delivery compartment.

The central partition 2^c terminates at its lower edge above side walls, or in other words, is cut away at its lower end so as to provide a transfer space so that the bottom bottle in the compartment 2^a may be transferred to what we term the delivery compartment. For effecting this transfer we have provided mechanism which preferably acts both to transfer the bottom bottle from the receiving to the delivery compartment, and to elevate the bottles successively in the delivery compartment so that the topmost bottle of the stack in the delivery compartment, which is in proximity to the upper end thereof, may be removed. This mechanism preferably comprises an oscillating member 5, preferably made of sheet metal, having side arms or lugs 5^a fulcrumed at a to the container walls, and having a curved portion 5^b which in the normal position of the parts, underlies the bottom-most bottle in the compartment 2^a and supports the stack of bottles therein. Means are provided by which the transfer device may be rocked on its pivots to cause the curved up end to pass out of the path of the lowermost bottle.

In Fig. 3 we have shown this member 5 in position to sustain the stack of bottles in the compartment 2^a, while in Fig. 3^a we have shown it rocked into bottle releasing position. When the curved up end is swung to the left and the lowermost bottle released, it will drop down in the receiving compartment but will be prevented from passing into the delivery compartment by reason of lack of space between the horizontally extending portion of the transfer device 5 and the bottom of the intermediate partition 2^c. If, however, the transfer device is again rocked to the position shown in Fig. 3, the curved up end will enter between the lowermost bottle and the next uppermost one to prevent further descent of the stack of bottles, while the said lowermost bottle will roll down the inclined surface of the transfer

device 5 into the position shown at 4^a, or in other words, will lie in the bottom of the delivery compartment. If now the transfer device is again rocked in a counter-clockwise direction Fig. 3, the bottle 4^a will be elevated in the delivery compartment and another bottle will be released from the receiving compartment to take its place.

A convenient manner of operating this transfer device is to provide a pair of reciprocating rods 6 suitably guided by the end walls of the delivery compartment and pivotally connected at their lower ends to the transfer device, and having their upper ends connected by links 7 to a hinged cover member 8 at the top of the delivery compartment.

Thus, when it is desired to remove a cooled bottle from the delivery compartment it is only necessary to lift up the cover 8, whereon the stack of bottles in the delivery compartment will be raised and the topmost bottle removed. Simultaneously, as before explained, a bottle will be released from the bottle receiving compartment and positioned by transfer to the delivery compartment on the return of the cover to closure position. To prevent the stack of bottles in the delivery compartment from dropping back after they have been raised, and thus interfering with the transfer of the fresh bottle from the receiving to the delivery compartment, we provide a pivoted retaining device 9 which is movable freely upward to permit the passage of the bottle, but it will resist downward movement thereof after it has passed the retaining device.

A hinged cover member 10 is preferably provided for the receiving compartment.

The container may conveniently be formed of sheet metal or any other suitable material of sufficient strength, and which will withstand the corrosive action of the ice water, the same being true of the other parts hereinbefore referred to.

In practice the delivery compartment would be kept full of bottles and the receiving compartment would be filled often enough to provide a storage supply for transfer to the delivery compartment. As the compartments are at all times kept filled with ice water, danger of breakage of the bottles by insertion or manipulation in the compartments, is avoided. At the same time, should any bottle become broken, or access to the storage container be required for this or for cleaning, or any other purpose, this is readily accomplished by lifting the container unit bodily from the receptacle box.

It will be obvious that the units may be made in different sizes to accommodate different sizes of bottles, this being illustrated in Fig. 1, wherein we have shown the two central units as of larger size than the side rows of units.

Having thus described our invention, what we claim is:—

1. In bottle handling apparatus, a receptacle comprising two vertically disposed receiving and delivery compartments communicating at the bottom and each being of a width corresponding substantially to the diameter of a bottle, a movable bottle retaining, releasing and transfer device located beneath the receiving compartment and adapted to support the lowermost of the series of bottles, and means operable from the top of the receptacle whereby the said transfer device may be actuated to transfer the bottle from the receiving to the delivery compartment. 70 75 80

2. The apparatus of claim 1, in which the transfer device comprises a rocking member having a ledge portion designed to successively release the lowermost bottle of the receiving compartment and a laterally extending portion which serves to guide the released bottle into the delivery compartment and elevate the same therein. 85

3. Apparatus according to claim 1, in which a hinged lid is provided at the top of the receptacle which is operatively connected with the transfer device. 90

4. The combination with an ice chest, of a bottle receptacle having an open bottom and a central vertical partition terminating short of the lower end of said receptacle and forming receiving and delivery compartments, a rocking transfer device located at the lower end of said receptacle below said partition and at the bottom of the receiving compartment for supporting the bottles in said receiving compartment, and an operating device whereby said supporting means may be operated from the top of the receptacle to transfer the lowermost bottle to the delivery compartment. 95 100 105

5. A bottle holding receptacle for removable insertion in ice chests comprising a casting having an open bottom and a vertical partition terminating short of the bottom and forming two compartments each of a width slightly exceeding the diameter of a bottle, a rocking member fulcrumed at the bottom of said receptacle and having a bottle supporting seat located at the lower end of the receiving compartments for supporting the pile of bottles therein, said rocking member projecting laterally into the delivery compartment, means extending to the delivery compartment and serving as bottle transfer and elevating means, and an operating rod pivotally connected to said rocking member at its lower end and extending upward to the top of the receptacle, and means in said delivery compartment for retaining the bottles elevated by said rocking member. 110 115 120 125

6. A bottle holding receptacle for ice chests having receiving and delivery compartments communicating at the bottom, 130

each being of a width slightly exceeding the diameter of a bottle, an oscillating transfer member located at the bottom of the receptacle having a curved portion located at the bottom of the receiving compartment, and side arms projecting into the delivery compartment, and bottle elevating means extending to the top of the delivery compartment

ment and connected at the lower end to said side arms.

In testimony whereof, we affix our signatures.
